UNITED STATES PATENT OFFICE.

EDWIN S. THURBER, OF BOSTON, MASSACHUSETTS.

HORSESHOE.

SPECIFICATION forming part of Letters Patent No. 276,647, dated May 1, 1883.

Application filed March 19, 1883. (No model.)

To all whom it may concern:

Be it known that I, EDWIN STANTON THURBER, of Boston, in the county of Suffolk, of the Commonwealth of Massachusetts, have invented a new and useful Improvement in Horseshoes; and I do hereby declare the same to be described in the following specification and represented in the accompanying drawings, of which—

10 Figure 1 is a top view, Fig. 2 a bottom view, Fig. 3 a front elevation, Fig. 4 a longitudinal and vertical section, Fig. 5 a side view, and Fig. 6 a horizontal section, of a horseshoe provided with my invention, the nature 15 of which is defined in the claims hereinafter presented. Fig. 7 is a side view of one of the calks.

The said invention is for securing the toe and heel calks to the shoe, and to render them 20 easily removable therefrom and others put in their places, as occasion may require. For this purpose each of the said calks is not only furnished with a dovetailed tenon to extend from it into a corresponding mortise made in 25 the shoe, but has a passage or hole made through such tenon to receive a wire which goes through such passage or hole and in a groove made in and around the shoe at its outer edge, all being essentially as represented.

30 In the drawings, A denotes the shoe, having at its toe and near each of its heels a dovetailed mortise, a, which extends upward into or through the shoe. Furthermore, there is in and around the shoe, at its outer edge, a

groove, b, which opens into each mortise. Each 35 calk B has a dovetailed tenon, c, extending from its upper end and adapted to fit the mortise in the shoe, and through such tenon transversely, and near its outer or smaller side, is a passage or hole, d, to receive a wire, C, which 40 is placed around the shoe and in the groove and goes through the calk-tenons. The groove holds the wire in place, and it and the wire operate to secure the calks to the shoe. The wire, at each end, may be bent at a right angle 45 and either extended into the shoe or lapped on its heels.

When the calks may become worn so as to be of little or no use they can easily be extracted from the shoe after removal of the wire 50 from it and them, and others or unworn ones of like construction may be substituted.

I claim—

1. The horseshoe grooved and mortised, substantially as described, for reception of a wire 55 and calks, as explained.
2. The horseshoe having a groove and dovetailed mortises arranged in it, substantially as described, in combination with calks provided with dovetailed tenons to fit the mortises, and 60 with a wire arranged in the groove and extended through such tenons, all being essentially as explained.

EDWIN STANTON THURBER.
